UNITED STATES PATENT OFFICE.

JOHANNES SARTIG, OF BERLIN-ZEHLENDORF, GERMANY.

TOBACCO DENICOTINING PROCESS AND APPARATUS.

Application filed April 30, 1926, Serial No. 105,862, and in Germany March 3, 1926.

This invention is concerned with a process of and apparatus for denicotining tobacco, tobacco waste and tobacco products. According to my invention the nicotine can be 5 easily and quickly eliminated or extracted from the tobacco, from tobacco waste or from finished tobacco products up to any small percentage desired and the extracted nicotine simultaneously be recovered. Since the tobacco is treated at the exclusion of air and at temperatures below 100° C. only and as any lixiviation of it does not take place, its 10 flavour and its contents of extract substances, that is its quality, remain fully preserved. 15 Since besides only small quantities of ammonia, a substance which exists in the tobacco in varying proportions anyway, are used in addition to water for the denicotinization of the tobacco treated, any contamination of the same by adventitious or "alien" 20 chemicals is avoided.

In the actual practice of my invention the material to be denicotined is, at the exclusion of air, so steamed or treated with an 25 aqueous atmosphere or evaporation of water obtained by heating the liquid within a closed receptacle to a temperature below 100° C. and under such conditions, that a deposition of condensed water cannot occur on or 30 within the material to be denicotined. I obtain this result by first heating the tobacco to the desired temperature and by exposing it thereafter to the action of the water evaporation while maintaining the temperature to below 100° C., so that any cooling down 35 of the tobacco or any condensation of water on or in it is prevented. Preferably I pass through the heated tobacco aqueous vapors or a water evaporation containing a slight 40 amount of ammonia and having the same temperature as the tobacco. The evaporation is after its passage through the tobacco condensed, returned to the original liquid again 45 evaporated and repassed through the tobacco and this cycle is maintained, until the desired denicotinization has been obtained. All 50 of the nicotine eliminated from the tobacco being contained in the final condensate can thus be recovered.

55 The new effect of my improved process consists in that the slight ammonia contents of the water evaporation frees the nicotine bound to vegetable acids upon passing through the tobacco under the conditions

60 tected against oxidation is taken up by and dissolved in the extracting atmosphere, subsequently condensed in the apparatus and that the continuously produced evaporation or volatilization of the ammonia containing liquid is continuously or repeatedly passed through the tobacco and subsequently condensed and reevaporated. As the nicotine 65 volatilizes more readily from the tobacco than from the condensate, the tobacco treated is denicotined and all of the nicotine expelled or extracted will finally be dissolved in the final condensate.

If during the treatment of a given charge 70 of tobacco fresh ammonia containing water is used once or several times a more quick and complete denicotinization of the tobacco can be obtained, this denicotinization proceeding besides the more quickly, the more the 75 temperature of the treatment approaches 100° C.

In the drawing Figs. 1 and 2 illustrate 80 cross-sections of two preferred embodiments of a denicotining apparatus in which my improved denicotining process may be carried out.

The tobacco 1 is piled loosely within a suitable container 2, for example in a wire basket or container, so that the surrounding atmosphere may easily pass through it; the container being so placed upon the perforated bottom 3 of a receptacle 4, that the tobacco is out of contact with the bottom wall 5 and the side walls 6 of the receptacle 4 which may be of any suitable material, for example iron. The top wall or cover 7 is then so applied to the receptacle 4 as to avoid access of air thereto, and the temperature of an outer heating bath 9 surrounding the receptacle 4 is raised by any suitable heating 90 means, such as a controllable gas flame 8. The temperature of receptacle 4 will now raise to any desired temperature below 100° C. and this temperature is maintained until the tobacco within the receptacle has reached 95 throughout the temperature below 100° C. selected. During this heating operation a vent cock 16 arranged at the top side of receptacle 4 is opened in order that the heated air may escape. Thereupon water 10 containing a slight quantity, for example 0,25%, 100 of ammonia and which preferably has before been heated to the desired temperature is, while cock 16 is still being open, admitted by a cock 11 into the space below the perforated 105

55 stated that the nicotine thus freed and pro-

110

wall or diaphragm 3 which may be of any suitable material, for example iron, the cocks 16 and 11 being then closed.

As a result of the outer heating of the receptacle 4 an evaporation of ammonia containing water will raise from the liquid 10 and create within the receptacle 4 an aqueous, hot atmosphere which passes through the tobacco and is charged with a portion of the nicotine freed by the ammonia from the tobacco, the evaporation eventually impinging against the top wall or cover 7 of receptacle 4. This wall 7 constitutes the bottom wall of a top receptacle 12 through which a cooling medium such as water, air or the like is flowing and which has inlet and outlet tubes 13 and 14 for this medium, as shown. The wall 7 is thus always kept at the desired cooling temperature and acts as a cooling or condensing surface for the warm water evaporation within the receptacle 4.

In the embodiment Fig. 1 the top or cover wall 7 is so shaped and inclined, that the liquid condensed on it in the receptacle 4 cannot drip off into the receptacle, but flows along the wall 7 down onto the side wall of receptacle 4 and is thus returned to the bottom wall 5 thereof and into the original liquid for further evaporation. Instead of the inclined wall 7 shown in Fig. 1, I can also use the conical wall 7 illustrated in Fig. 2 as a cooling surface.

By the outer heating of wall 5 and of the side walls 6 of receptacle 4 an ammonia containing water evaporation or aqueous vapor is continuously rising from the liquid 10 on the bottom wall 5 of receptacle 4 and passing through the tobacco having the same temperature, so that any condensation within the tobacco is prevented. The evaporation is continuously taking up nicotine from the tobacco and is thereupon condensed while containing such nicotine within the receptacle 4 on the cooled top wall 7 and the condensate is flowing past the said top wall 7 to the side wall 6 of receptacle 4 and finally returned to the liquid on the bottom wall 5. At the end of the treatment this nicotine containing liquid may be discharged through cock 15. If desired the receptacle 4 can be constructed without the particular cooling compartment 12, so that the wall 7 will be the topmost wall of the apparatus and acts as a cooling wall by its direct heat exchanging contact with the outer air.

In carrying out the improved denicotining process at a heating bath temperature of 75° C. tobacco treated for six hours and having a nicotine contents of 1,38% yielded a dry tobacco having only a few percents of moisture and a nicotine contents of 0,20%. After a further treating period of three hours the same tobacco still contained 0,08% nicotine

only, while the extracted nicotine was contained in the water-clear liquid 10 on the bottom wall 5 of receptacle 4.

Finished tobacco products, even cigars with a closed tip at their one end or cigarettes with their delicate paper wrapper can be denicotined in the way indicated without being damaged or without detriment to their outer appearance.

What I claim is:

1. The denicotining process which consists in preheating the material to be denicotined within a closed receptacle to a temperature below 100° C., producing within the same receptacle an evaporation of ammonia containing water at the exclusion of air and by substantially the same rise of temperature, 80 passing the said evaporation through the material to be denicotined while the said temperature is being maintained, condensing the water evaporation within the said receptacle after its passage through the material 85 to be denicotined and returning the condensate thus obtained at the exclusion of its contact with the material to be denicotined to the original liquid, and continuing such procedure until the desired denicotinization 90 has been obtained.

2. A denicotining apparatus comprising a closed receptacle adapted to receive in its bottom end a denicotining liquid, a support arranged above the bottom wall and adapted to receive the material to be denicotined so as to avoid its contact with the denicotining liquid, means permitting to heat the said liquid and the material to be denicotined to a temperature below 100° C. while permitting the top of the receptacle to remain cool and adapted to act as a condensing means, and means for returning the condensate from the top side of the said receptacle to the denicotining liquid at the exclusion of its contact with the material to be denicotined. 100

3. A denicotining apparatus comprising a closed receptacle adapted to receive in its bottom end a denicotining liquid, a support arranged above the bottom wall and adapted to receive the material to be denicotined so as to avoid its contact with the denicotining liquid, means permitting to heat the said liquid and the material to be denicotined to a temperature below 100° C. an inclined top 110 wall on the said receptacle adapted to act as a vapor condensing and condensate deflecting surface and constituting means for returning such condensate to the denicotining liquid at the exclusion of any contact of the condensate with the material to be denicotined, and means for cooling the said top wall. 115

In testimony whereof I affix my signature.

JOHANNES SARTIG.
